Specification for Design.

Patented Feb. 1, 1921.

Application filed May 7, 1920. Serial No. 379,672. Term of patent 14 years.

To all whom it may concern:

Be it known that we, ALFRED INGRAM and HARRY INGRAM, citizens of the United States, residing at Brooklyn, in the county of Kings and State of New York, have invented a new, original, and ornamental Design for a Closure-Cap for a Jar or Similar Article, of which the following is a specification, reference being had to the accompanying drawings, forming a part thereof, and in which—

Figure 1 is a top view;

Fig. 2 a front side view;
Fig. 3 a side view taken from either side of Fig. 2, and

Fig. 4 a side view taken at an angle of about forty-five degrees from Fig. 2, of a closure cap embodying our design.

We claim:

The ornamental design for a closure cap for a jar or similar article, as shown.

ALFRED INGRAM.
